(57) **CLAIM**

The ornamental design for a vibrating exfoliation device, substantially as shown and described.

DESCRIPTION

FIG. 1 is a perspective view of a preferred embodiment of my design;

FIG. 2 is a front elevation view of the preferred embodiment of my design;

FIG. 3 is a rear elevation view of the preferred embodiment of my design;

FIG. 4 is an elevation view showing one side of the preferred embodiment of my design, the other side being the mirror image thereof;

FIG. 5 is a top elevation view of the preferred embodiment of my design; and,

FIG. 6 is a bottom elevation view of the preferred embodiment of my design.

The broken lines shown in the drawings illustrate portions of the article and form no part of the claimed design.
